COMBINED PIN CONTAINER AND POURER

George Abe Laughton, Lawsonford, England

Application June 8, 1954, Serial No. 30,871

Term of patent 14 years

(CL. D58—17)

FIG. 1.

FIG. 5. FIG. 2.

FIG. 3.

FIG. 4.

I claim:

The ornamental design for a combined pin container and pourer, as shown.
